[57] CLAIM

The ornamental design for a splice element for a ladder safety rail, as shown.

DESCRIPTION

FIG. 1 is a perspective view of the splice element for a ladder safety rail, showing my new design;
 FIG. 2 is an elevational view of one side thereof;
 FIG. 3 is an elevational view of one end thereof;
 FIG. 4 is a top plan view thereof;
 FIG. 5 is an elevational view of the opposite side thereof;
 FIG. 6 is an elevational view of the opposite end thereof; and
 FIG. 7 is a bottom plan view thereof.
